UNITED STATES PATENT OFFICE.

JAMES COOK DOWNIE, OF PEBBLE BEACH, CALIFORNIA.

AMUSEMENT DEVICE.

Application filed February 19, 1923. Serial No. 620,046.

To all whom it may concern:

Be it known that I, JAMES COOK DOWNIE, a citizen of the United States, residing at Pebble Beach, in the county of Monterey and 5 State of California, have invented new and useful Improvements in Amusement Devices, of which the following is a specification.

This invention relates to new and useful 10 improvements in amusement devices, and has particular reference to a game which will simulate the plays usually made during a golf game.

The principal object of this invention is 15 to provide simple means whereby a player may strike at a golf ball thereby causing a dummy ball to travel over a field for a distance depending upon the strength of the drive.

20 A still further object is to provide means for returning the dummy ball to its initial or starting position after the same has traveled across the course.

A still further object is to provide a device of this character which will be cheap to manufacture and one which will stand hard usage without the parts becoming deranged.

Other objects and advantages will be apparent during the course of the following 30 description.

In the accompanying drawings forming a part of this specification, and in which like numerals are employed to designate like parts throughout the same,

35 Figure 1 is a top plan view of my device as a whole,

Figure 2 is a side elevation of Figure 1, partly broken away in order to better illustrate the interior mechanism,

40 Figure 3 is a cross section taken on the line 3—3 of Figure 2, looking in the direction of the arrow,

Figure 4 is a fragmentary detail view of the audible signal mechanism,

45 Figure 5 is a cross section taken on the line 5—5 of Figure 1, and

Figure 6 is a cross section taken on the line 6—6 of Figure 5, looking in the direction of the arrow.

50 In producing an amusement device it is essential that the same simulate a popular pastime in order to be attractive to the average individual.

I have therefore produced an amusement 55 device having a putting green where the player stands and strikes at a ball held a

slight distance above the surface of the green and have further provided a fair way which is painted to represent a distant scene, such as the player would view upon 60 the golf links, thus producing a game which is attractive to the average individual.

In the accompanying drawings wherein for the purpose of illustration is shown a preferred embodiment of my invention, the 65 numeral 5 designates a platform elevated a suitable distance above the ground and provided with a driving tee 6, which is preferably made of carpet, and set flush with the top of the platform 5. 70

An opening 7 is centrally positioned in the carpet and extends through the platform so as to provide for the rotation of a series of balls 8. These balls are mounted upon rods 9, which rods are in turn secured to a shaft 11. This shaft 11 is mounted in bearings as shown at 12 and 13, which bearings are secured to the under surface of the platform 5 as best shown in Figure 6. 75

A ring-like brace 14 serves to steady the 80 rods 9 with respect to each other. By now viewing Figure 6, it will be noted that the shaft 11 carries a spool 16 and a drum 17.

A cord 18 has one end secured to the spool 16 and has its opposite end trained 85 over a series of pulleys as shown at 19, 21, 22 and 23 and is secured to a yoke 24 carried by the pulley 21.

A weight 26 is secured to the pulley 23, the purpose of which will be later seen. A 90 cable 27 is wrapped about the drum 17 and extends beneath a runway 30. It is obvious that this runway 30 may be omitted if desired.

Positioned at the opposite end of the runway from the platform 5 are standards 28 and 29. The standards 28 serve to support 95 the front end of a rectangular housing 31, while the standards 29 serve to support the rear end of the housing and by viewing 100 Figures 1 and 2, it will be noted that this housing tapers from the standards 28 toward the standards 29 forming a truncated cone 31, which is laid upon its side.

Suitable braces 32 are provided and function in the usual manner. By viewing Figure 3 it will be noted that the interior of this housing is painted so as to represent a golf course and its customary landscape. The small end of the housing is designated 105 by the numeral 33. At the point of juncture of the back and the bottom, I provide a 110

pulley 34 and I likewise provide a pulley 36 as shown in dotted lines in Figure 2, at the forward end of the bottom portion of the housing 31.

5 Similar pulleys 37 and 38 are positioned nearer the end of the runway at a point beneath the pulley 36. By viewing Figure 2, it will be noted that the cable 27 is passed beneath the pulley 38 over the pulley 34, 10 over the surface of the bottom of the housing, over the pulley 36, under the pulley 37 and back to its point of commencement. At a suitable point within this cable I place a tension spring 39 in order that the cable 15 may at all times be kept taut.

At 41 I have shown a miniature golf ball secured to the cable 27. This golf ball is adapted to travel from a point adjacent the pulley 36 to a point adjacent the pulley 34. 20 When this ball has reached a point adjacent the pulley 34, it will strike a trap 42 hinged as at 43 which trap will contact a binding post 44, which binding post is connected by a wire 46 to a battery 47, and is in turn 25 connected to a bell 48, the opposite side of which is connected by a wire 49 to the trap 42.

Painted upon the lower surface of the housing 31 are indicia which when the ball 30 reaches the same the extent or distance of the drive may be determined.

The operation of my device is as follows:—

The player stands upon the platform 5 35 swinging his club in such a manner as to strike one of the balls 8 which is projecting through the opening 7. This striking of the ball imparts rotation to the shaft 11 also rotating the spool 16 and drum 17. As the 40 spool 16 rotates in a clock wise direction the cable 18 is wound upon the spool which also causes the weight 26 to rise toward the under-surface of the platform at the same time the rotation of the drum 17 causes the 45 cable 27 to move together with its attached miniature golf ball 41. This golf ball proceeds over the lower surface of the housing and the player watches the same until it comes to a stop over a marking which indicates the extent of his drive.

Should the drive be of a sufficient force the miniature ball will contact the trap 42 and complete the circuit between the battery 47 and the bell 48, thus giving an audible 55 signal.

As soon as the ball 41 has come to a point

of rest the weight 26 starts to function and travel downward. This downward travel causes an unwinding of the cable from the spool 16 with the result that the cable 27 60 moves in a reverse direction, thus returning the miniature ball 41 to its natural or starting position.

It is to be understood that the form of my invention herewith shown and described is 65 to be taken as a preferred example of the same, and that various changes in the shape, size and arrangement of parts may be resorted to without departing from the spirit of the invention or the scope of the sub- 70 joined claims.

Having thus described my invention, I claim:—

1. In a device of the character described, a platform, a housing, a runway extending 75 between said housing and said platform, a shaft positioned beneath said platform, a series of balls radially disposed with respect to said shaft, a drum mounted on said shaft, a cable secured about said drum, said cable extending beneath said runway to a point beneath said housing, one portion of said cable being trained so as to lie parallel with the upper surface of the floor of said housing, a ball secured to said cable in such 80 a manner as to move over the floor of said housing when said cable is moved, and means for maintaining said cable taut.

2. In an amusement device, a housing, comprising a rectangular structure having 90 tapering sides, the interior of said housing representing a portion of a golf course, a miniature ball adapted to move over said course, a platform spaced from said housing, a shaft mounted beneath said platform, a 95 series of balls radially disposed on said shaft, a spool located on said shaft, a weight positioned beneath said platform, a plurality of pulleys mounted beneath said platform, a cord secured to said weight, and passing over the said pulleys secured beneath said platform, the opposite end of said cord being secured to said spool, and means connected with said shaft for causing said first mentioned ball to move 100 over said course when said shaft is rotated through the action of striking one of the radially disposed balls.

In testimony whereof I affix my signature.

JAMES COOK DOWNIE.
